US00D998380S

(12) United States Design Patent (10) Patent No.: US D998,380 S
(45) Date of Patent: * Sep. 12, 2023

(54) PILLOW

(71) Applicant: Luqi Yan, Nantong (CN)

(72) Inventor: Luqi Yan, Nantong (CN)

() Term: 15 Years

(21) Appl. No.: 29/798,830

(22) Filed: Jul. 11, 2021

(30) Foreign Application Priority Data

Mar. 5, 2021 (CN) 202130120298.0

(51) LOC (14) Cl. 06-09

(52) U.S. Cl.

USPC D6/601

(58) Field of Classification Search

USPC D6/595, 596, 597, 601, 604; D24/183, D24/184, 185; D21/803, 804, 805, 809;
